UNITED STATES PATENT OFFICE.

HARRY A. DOUGLAS, OF BRONSON, MICHIGAN.

LOCKING MECHANISM FOR INTERNAL-COMBUSTION ENGINES.

Application filed June 27, 1925. Serial No. 40,082.

My invention relates to power plants and is of particular service in connection with those power plants which are employed for operating automotive vehicles, the invention being especially useful in connection with power plants that employ internal combustion hydrocarbon engines, the invention in some of its characteristics relating particularly to such power plants.

My invention involves the employment of means for locking a power plant in non-operative adjustment and the provision of electro-magnetically controlled mechanism for adjusting the power plant to a usable condition. In carrying out my invention I employ releasing electro-magnetic mechanism having a plurality of controlling switches and preferably of energizing windings with a controlling circuit for each. In order to effect the operation of the releasing electromagnetic mechanism it is necessary to operate all the switches and to establish each of the plurality of circuits of the electromagnetic mechanism at one time, any number less than the whole number of these circuits being incapable of effecting the operation of the electromagnetic mechanism. Any person that is unfamiliar with the equipment, such as a thief desiring to steal an automobile, might not have so much difficulty in establishing one of these circuits but his difficulties would be increased if he seeks to establish them all, due to the confusion that would be experienced in selecting the proper conductors and effecting the connection thereof with the source of current employed to energize the windings. The time ordinarily would not permit of the experimentation required to gain simultaneous control over all the circuits.

In the preferred embodiment of my invention the electromagnetic mechanism is employed to adjust means that will permit the application of operating energy to the engine or motor of the power plant. In the case of an internal combustion engine I employ an additional throttle valve located between the carburetor and the engine, this valve being preferably adapted for closure by a spring against the force of which the valve is opened by the electromagnetic mechanism which desirably functions through the intermediation of a step by step device which is operated a step each time a plurality of magnet windings are together energized.

The invention will be more fully explained in connection with the accompanying drawings in which Fig. 1 is a diagrammatic view illustrating the preferred embodiment of my invention employed in connection with the power plant of an automotive vehicle; Fig. 2 is a sectional view of the preferred form of switching mechanism taken on line 2-2 of Fig. 3; Fig. 3 is a sectional view on line 3-3 of Fig. 2; Fig. 4 is a sectional view on line 4-4 of Fig. 3; Fig. 5 is a sectional view on line 5-5 of Fig. 2; Fig. 6 is a sectional view of the locking mechanism that is preferably employed in connection with the switching mechanism, this view being taken on line 6-6 of Fig. 3; Fig. 7 is a front elevation of the locking mechanism; Fig. 8 is a longitudinal sectional view taken through a portion of the piping extending from the carburetor to the engine, the added throttle valve in this piping and the mechanism for placing this throttle valve in open and closed positions; Fig. 9 is a sectional view on line 9-9 of Fig. 8; Fig. 10 is a sectional view on line 10-10 of Fig. 8; Fig. 11 is a sectional view on line 11-11 of Fig. 8; Fig. 12 is a sectional view on line 12-12 of Fig. 11, and Fig. 13 is another diagrammatic view illustrating changed positions of some of the parts shown in Fig. 1.

The power plant illustrated includes an internal combustion engine having four cylinders, 1, 2, 3 and 4, each cylinder having an ignition circuit inclusive of the sparking terminals 5, included in a conductor grounded at one end and connected with a contact 6 at its other end. The four contacts 6 of the four ignition circuits are arranged in a circular row which is concentric with a revoluble switching arm 7 adapted to engage the contacts 6 in succession. The switch arm 7 is carried upon a shaft 8 which is driven by the engine through the intermediation of an engine driven pulley 9 and a pulley 10 driven by the pulley 9 through the intermediation of a belt 11. The shaft 8 also carries a circuit interrupting cam wheel 12 that serves to vibrate the circuit interrupting switch 13 which is included in an inducing ignition circuit arranged to be supplied with current from the battery or generator 14 of direct current, or from the direct current magneto generator 15, in accordance with common practice. The magneto generator 15 is

driven by the pulley 16 upon the same shaft with the pulley 9, the pulley 16 driving the pulley 17 that is upon the shaft 18 on which the armature of the magneto generator is disposed, as is well understood by those skilled in the art. When it is desired to charge the battery a suitable switch is closed, the hand switch 19 being shown for this purpose by way of illustration.

- 10 In the system shown the battery 14 is included in the inducing circuit when the power plant is first set into operation, whereafter this battery is cut out of the inducing circuit and is replaced by the magneto generator 15 in this circuit. The inducing circuit when including the battery may be traced from ground through the battery, the switch contact 20 then engaging contact 21 as will be explained, the inducing winding 22, the circuit interrupting switch 13 to ground, the contacts of the switch 13 being desirably shunted by a condenser 23, as is usual. The inducing circuit when containing the magneto generator may be traced from ground through the magneto generator, the conductor 24, the spring contact 25, the contact 21 then engaging spring contact 25 as will appear, the inducing winding 22, the interrupting switch 13 to ground.
- 20 The spring switch contact 21 is mechanically adjusted by the operating arm 26 having a hump 27 arranged to enter notches 28, 29, and 30 formed in the periphery of a ring 31. The notches are of different depths, notch 30 being shallowest, notch 29 the deepest, and notch 28 of a depth midway between the depth of notches 29 and 30. In operation the ring 31 is turned clockwise as viewed in Fig. 1. When the ignition circuit is to include the battery and exclude the magneto generator, the hump 27 upon arm 26 is received in the notch 29 whereby spring contact 21 is permitted to engage contact 20. When the magneto is to be included in the ignition circuit in place of the battery, the ring is turned a little further to bring the hump 27 into the notch 30, whereupon the spring contact 21 is swung by arm 26 into engagement with the contact 25. When the switching mechanism is to be brought into idle adjustment in which neither battery nor magneto generator is in the ignition circuit, the ring 31 is turned to bring the hump 27 into engagement with the notch 28 to adjust the arm 26 to hold the contact 21 in mid position between the contacts 20 and 25 and out of engagement with both of these contacts. The induced circuit includes the induced coil 32, grounded through the switch 13 and condenser 23, the rotating switch arm 7, the particular contact 6 happening to be engaged by the switch arm 7 and the contacts 5 pertaining to this particular contact 6.
- 65 The engine illustrated is operated by air

which is carbureted by gasoline admitted from a gasoline tank 33 into the float chamber 34 of a carburetor, this chamber containing a float 35 which is in controlling relation to a needle valve 36 which prevents, permits and regulates the admission of gasoline to the float tank. The gasoline is admitted from this float tank through a port therein that is controlled by a needle valve 37, the gasoline finding entry into the mixing chamber 38 of the carburetor. This mixing chamber is included as a portion of piping 39 that connects the intake ports and intake manifold of the engine with the carburetor and external air. This carburetor includes an air valve 40 and a throttle valve 41, in accordance with common practice. I add a throttle valve 42 between the engine on the one side and the carburetor and throttle valve on its other side. The added throttle valve 42 is fixed upon a shaft 43. A coiled spring 44 serves, when free to act, to turn the valve 42 to a closed position. A segmental ratchet 45 is fixed upon the shaft 43. A pawl 46 is adapted to turn the ratchet 45 step by step in a clockwise direction to turn the shaft 43 and the valve 42 on the shaft step by step to a fully open position (Fig. 13), the opening of the valve 42 being completed during the last few steps of movement of the ratchet. The battery is not connected in the inducing ignition circuit until the valve is in its fully open position so that the power plant is not operable until the valve reaches this fully open position. The holding dog 47 holds the ratchet 45 to the position to which it is turned and against the force of the spring 44. A pin 48 upon the ratchet 45 is employed to break the connection of the dog 47 with the ratchet when the spring 44 is to be permitted to function to place the valve 42 in the closed position illustrated in Fig. 1. This pin is caused to function when the ratchet is stepped another tooth beyond the number of steps required to place the valve 42 in a completely opened position, the pin 48 operating when the ratchet 45 is given this additional movement, to engage the dog releasing arm 49 that is journaled upon the shaft 43, the arm 49 being then moved by the pin 48 to engage and lift the dog 47 out of engagement with the ratchet 45, whereupon the spring 44 is permitted to function.

I desirably employ electro-magnetic mechanism for operating the pawl 46 step by step. This electromagnetic mechanism includes three coils 50, 51 and 52 arranged upon a common magnetizable iron core 53. The coils are cumulatively wound. The two coils 50 and 51 are adapted for serial connection and therefore together constitute one winding. The coil 52 itself constitutes another winding. Each winding is included in a circuit individual thereto, it being necessary

to close the circuits of both windings in order to magnetize the core 53 sufficiently to attract the armature 54 upon which the pawl 46 is pivoted. A spring 55 serves to restore the armature 54 and the pawl 46 each time the core 53 is deenergized. The circuits for the coils 50, 51 and 52 include the battery 14 which is common to these circuits. Assuming that the valve 42 is in the fully closed position illustrated in Fig. 1, in order to fully open the valve from this position to the position shown in Fig. 13, the circuits of the three coils 50, 51 and 52 are simultaneously intermittently closed and opened. This may be done by means of a ring 56 of insulation having thereon a series of teeth 57, corresponding in number to the number of step by step movements of the ratchet 45 required to turn the valve 42 to a completely open position. In this instance there are eight such teeth. This ring, as is also the ring 31, is locked when the valve 42 is in a completely closed position, as will appear. It is therefore necessary for an unauthorized user to know the number of interruptions required to step the valve 42 to its fully opened position. The wheel 56 is turned clockwise as viewed in Fig. 1, and as it is turned the teeth 57 are brought successively into engagement with the contact arm 58. The contact arm 58 is, consequently, engaged with the spring contact 59 and this spring contact 59 is engaged with the contact 60, the three contacts 58, 59 and 60 being electrically connected each time the contact arm 58 is completely raised by the engaging tooth 57. The circuits for the magnet coils 50, 51 and 52 are consequently closed and opened each time a tooth 57 rides into and out of engagement with the contact arm 58. The circuit for the magnet winding 50, 51 may be traced from the grounded battery 14 through the contact 60, the contact 59, the contact 58 and coil 50, the contact 61, the contact 26 then pressed into engagement with the contact 61 by an unnotched portion of the ring 31, the coil 51 to ground. The circuit is at the same time established for the winding 52 traceable from the grounded battery 14 through the contacts 60 and 59, winding 52, to ground. When the ring 56 has been turned to close and open the circuits thus traced eight times, the shaft 43 has been turned to place the valve 42 in a completely open position, Fig. 13, the spring 44 being at the same time placed under increased tension by the turning movement of the shaft 43. When the valve is in this completely closed position, the hump 27 upon arm 26 is locked in the notch 29, to include the battery 14 initially in the inducing circuit as hitherto traced. When the engine has been set into operation the ring 31 is turned to bring the hump 27 into the notch 30 in which the magneto generator 15 is substituted for the battery 14 in the inducing circuit. When it is desired to stop the engine and to lock it against unauthorized use, the ratchet 45 is given another step of movement, a result which is occasioned by turning the wheel 56 sufficiently to bring the tooth 62 into engagement with the switch arm 58 and thereby bring this switch arm into electrical connection with both contacts 59 and 60, whereupon the three coils 50, 51 and 52 are again energized to cause the pin 48 to turn the dog releaser 49 sufficiently to lift the dog 47 out of holding engagement with the ratchet 45, whereupon the spring 44 will turn the valve 42 to a completely closed position. When the valve is closed the dog releaser 49 is removed from engagement with the dog 47 to permit this dog to function in the next cycle of operations. It is understood that when the tooth 62 thus functions the contacts 26 and 61 are engaged, due to the fact that the hump 27 upon the arm 26 is engaged by another unnotched portion of the ring 31.

Referring more particularly to Fig. 3, it will be observed that the rings 31 and 56 are mechanically united by means of the riveting pins 63. The ring 56 has a hub extension 64 which receives the lock barrel 65. The hub 64 and lock barrel 65 are formed so that the ring 56 will be turned when the lock barrel 65 is turned. This lock barrel is mounted to turn in a lock casing 66. Inwardly spring pressed plungers 67 are provided in the lock casing 66 and tumblers 68 are provided in the lock barrel 65. The key 69 receivable in the lock barrel 65 places the outer ends of the tumblers 68 at the periphery of the lock barrel 65 thereby forcing the plungers 67 outwardly and permitting the lock barrel to turn the rings 31 and 56. The key may be withdrawn when the tumblers 68 are brought into register with the plungers 67 to lock the barrel 65 against rotation, the valve 42 then being in completely closed position. The rings 31 and 56 together with the contacts operated thereby are located within a casing 70 closed at its rear end by a disc of insulation 71, this disc 71 being assembled with the casing by means of bayonet pins 72 on the disc that enter corresponding bayonet slots in the casing. A mounting plate 73 is assembled with the front end of the casing, this mounting plate being provided with holes 74 through which assembling screws may be passed. A housing 75 encloses the locking mechanism, this housing being surrounded by the mounting plate and fixedly assembled with the casing 70 and the lock casing 66.

Changes may be made without departing from my invention.

Having thus described my invention, I claim:

1. The combination with an internal com-

bustion engine including a member movable between two positions in one of which it permits operation of the engine and in the other of which it prevents operation of the engine; of electro-magnetic means for moving said member, and switch means controlling the operation of said electro-magnetic means, said electro-magnetic means being composed of a plurality of separate windings and said switch means including a plurality of switches one in controlling relation to each winding.

2. The combination with an internal combustion engine including a fuel supply conduit and a valve movable to control the flow of fuel through said conduit; of electro-magnetic means for moving said valve, and switch means controlling the operation of said electro-magnetic means, said electro-magnetic means being composed of a plurality of separate windings all of which are required to be energized simultaneously to effect movement of said valve, and said switch means including a plurality of switches connected together for collective operation and operable to close circuits through said windings successively.

3. The combination with an internal combustion engine including a member movable between two positions in one of which it permits operation of the engine and in the other of which it prevents operation of the engine; of an electro-magnetically operated pawl and ratchet mechanism for moving said member, and means controlling the operation of said mechanism, said mechanism including a plurality of separate windings all of which are required to be energized simultaneously to cause said mechanism to effect movement of said member, and said con-

trolling means including a plurality of switches individual to said windings.

4. The combination with an internal combustion engine including a member movable between two positions in one of which it permits operation of the engine and in the other of which it prevents operation of the engine; of yieldable means constantly urging said member towards a position in which it prevents operation of the engine, electro-magnetic means for moving said member to a position in which it permits operation of the engine, and means controlling the operation of said electro-magnetic means, said electro-magnetic means including a plurality of windings all of which are required to be energized simultaneously to cause said electro-magnetic means to effect movement of said member, and said controlling means including a plurality of switches individual to said windings.

5. The combination with an internal combustion engine including a member movable between two positions in one of which it permits operation of the engine and in the other of which it prevents operation of the engine; of electro-magnetic means for moving said member, and means controlling operation of said electro-magnetic means, said electro-magnetic means including a plurality of separate windings adapted to be energized collectively intermittently to impart a step-by-step movement to said member, and said control means including a plurality of switches connected together for collective operation and operable to close circuits through said windings successively.

In witness whereof, I hereunto subscribe my name.

HARRY A. DOUGLAS.
